J. F. Johnson, Atty.

UNITED STATES PATENT OFFICE.

JOHN C. CARLSON, OF CHICAGO, ILLINOIS.

DEVICE FOR INDICATING THE LENGTH AND HANG OF COAT-SLEEVES.

1,390,340.

Specification of Letters Patent. Patented Sept. 13, 1921.

Application filed September 18, 1920. Serial No. 411,213.

To all whom it may concern:

Be it known that I, JOHN C. CARLSON, a citizen of the United States, residing at Chicago, in the county of Cook and State of Illinois, have invented certain new and useful Improvements in Devices for Indicating the Length and Hang of Coat-Sleeves, of which the following is a specification.

Heretofore coat makers in preparing a coat for a "try on" baste in the sleeves, and when the coat is tried on, if the sleeves do not hang properly or are not of the proper length, the sleeve is marked and then ripped out, the shoulder of the coat is then opened and changed by sometimes taking up or letting out an inch or more of the material, with the result that the sleeve length and the hang of the sleeve will be lost. In making the sleeve, the inside sleeve seam in soft goods will sometimes stretch fully half an inch resulting in considerable difficulty and inconvenience and the loss of the entire calculation as to the sleeve.

To overcome these difficulties and objections and to provide an improved device by means of which the length and hang of the coat sleeve may be ascertained and indicated, thereby obviating the necessity of making the sleeve for a "try on" and alteration, and at the same time insuring accuracy in the length and hang of the sleeve is one of the objects of the present invention.

A further object is to provide an improved device of this character which will be of a simple and cheap construction and by means of the use of which the proper length and hang of the sleeve may be marked or indicated upon the body of the coat, so that the sleeves may be formed of the proper length and properly positioned in the coat, thereby obviating the necessity of trying the coat and sleeve on for that purpose.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention and in which—

Figure 1 is a view showing the manner of using this invention.

Fig. 2 is a perspective view of the device.

Fig. 3 is a diagrammatic view of a portion 55 of a coat showing the sleeve indication marked thereon.

Fig. 4 is a detail sectional view taken on line 4—4 Fig. 2.

As shown in the drawing the numeral 10 60 designates a sleeve section constructed in the ordinary and well-known manner in which sleeves are constructed and this sleeve section 10 may be of any desired length, but is preferably somewhat shorter than the 65 sleeve to be applied to the coat.

Arranged at the top of the sleeve section 10 is a draw string 11 preferably elastic and which will contract the upper end and cause the same to be bound upon the arm of the 70 person, but may be released so as to permit the sleeve section to be freely adjusted lengthwise of the arm, but will maintain the sleeve section in its adjusted position.

This sleeve section 10 is preferably finished as the lower part of an ordinary sleeve so that when placed upon the arm of the person it will have the appearance of a portion of a coat sleeve.

Secured adjacent the lower edge 12 of the 80 sleeve is a gage 13 which may be of any desired size and configuration, but is preferably provided with a horizontal straight edge 14 and a vertical straight edge 15. This gage 13 is secured to the sleeve section in any 85 suitable manner preferably by sewing the body portion 16 thereof within the sleeve section so that the straight edge 14 of the gage will stand in close proximity to the lower front corner 17 of the sleeve section. 90

Pivottally connected with the gage 13 is a scale or rule 18 having indications or graduations 19 thereon. This scale 18 is pivotally connected as at 20 with the gage 13 so that when the sleeve section 10 is placed upon the arm the scale 18 will depend therebelow and will have a free swinging movement with respect thereto, so as to permit the scale to assume a proper position with respect to the hand of the person when the 100 sleeve section is in position.

Slidably mounted upon the scale 18 is an element 21 which is adapted to be secured in its adjusted position in any suitable manner such as by means of a clamping screw 105 22, and the free end of the scale 18 is prefer-

ably deflected as at 23 so as to prevent the element 21 from dropping off of the scale 18.

The element 21 projects laterally beyond the face of the scale 18 for any desired distance.

Two of these devices are employed, one for each arm of the person.

In use the coat, indicated by the reference numeral 24, is put on with the sleeves omitted therefrom. The sleeve sections 10 are then placed upon the arms of the person and one is adjusted lengthwise of the arm until the lower edge 12 of the sleeve section assumes the desired position with respect to the hand of the wearer. This adjustment will be permitted by reason of the yieldable element 11 at the top of the sleeve. When the sleeve section is positioned, the scale 18 will swing in a proper or vertical position below the end of the sleeve and adjacent the hand of the wearer. When the arm is inserted into the sleeve section the sleeve section will be filled out, that is to say, the lower front corner 17 of the sleeve section will assume the position shown in Fig. 1 with respect to the gage 13, as the corner of the sleeve section will move away from the straight edge 14 of the gage. The arm of the wearer is then held closely to his side so that the gage 13 will rest against the forward portion of the coat 24. A mark or indication is then made along the straight edge 14 and also along the straight edge 15 upon the coat, with chalk or otherwise, to form the indications 25 (see Fig. 3.) The mark along the straight edge 14 or at the top of the gage 13 will indicate the length of the coat sleeve, and the mark or indication at the side or along the straight edge 15 will indicate the hang of the sleeve because when the sleeve is sewed into the coat, after the coat is taken off, the lower front corner of the coat sleeve corresponding to the lower front corner 17 of the sleeve section 10 will be properly positioned with respect to the indication 25 on the coat 24. This is accomplished by reason of the fact that the lower edge of the sleeve will stand adjacent the indication made along the straight edge 14 while the front edge of the sleeve will coincide with the indication or line made along the straight edge 15.

After the indications have been thus made on the coat and before the sleeve section 10 is removed from the arm, the element 21 is adjusted along the scale 18 until the element contacts with the tip of the thumb of the wearer, and this will give the measurement from the bottom of the sleeve to the end of the thumb. This measurement on the scale 18 is now measured on the scale carried by the other sleeve section, that is from the end of the thumb to the bottom of the sleeve section and should the sleeve

section 10 on the other arm be too low or 65 too high to cause the element 21 on the respective element 18 to contact with the thumb of the other hand after having been set, then the sleeve section 10 is adjusted lengthwise of the arm until the element 21 70 does contact with the thumb. This will give the proper length of the other coat sleeve. After this operation the same indications are made on the other side of the coat to indicate the length and hang of the 75 other sleeve.

After these indications have been obtained, and when the sleeve is to be sewed into the coat, all that is necessary is to measure from the sleeve length marked on 80 the coat and thus obtained to one inch below the arm-hole notch 26, and this will indicate the correct length of the sleeve.

While the preferred form of the invention has herein been shown and described it is 85 to be understood that various changes may be made in the details of construction and in the combination and arrangement of the several parts within the scope of the claims without departing from the spirit of this 90 invention.

What is claimed as new is:—

1. A device for indicating the length and hang of a coat sleeve embodying a scale for designating a point to be indicated upon the 95 body of a coat, and means for attaching said scale to the arm of the person.

2. A device for indicating the length and hang of a coat sleeve embodying a scale for designating a point to be indicated upon the 100 body of a coat, means for attaching said scale to the arm of the person, a gage co-operating with and adjustable with respect to the said scale into engagement with one of the finger tips, and means for maintaining 105 the gage in its adjusted position.

3. A device for indicating the length and hang of a coat sleeve embodying a scale for designating a point to be indicated upon the 110 body of a coat, means for attaching said scale to the arm of the person, a gage co-operating with and adjustable with respect to the said scale into engagement with one of the finger tips, and means for maintaining 115 the gage in its adjusted position, the said scale being adapted for free swinging movement with respect to the arm and adjacent the hand.

4. A device for indicating the length and hang of a coat sleeve embodying an indicator 120 for designating a point to be indicated or marked upon the body of a coat, and means for releasably attaching the indicator to the arm of a person whereby the indicator may be adjusted in a direction lengthwise of the arm.

5. A device for indicating the length and hang of a coat sleeve embodying an indi-

- cator for designating a point to be indicated or marked upon the body of a coat, means for releasably attaching the indicator to the arm of a person whereby the indicator 5 may be adjusted in a direction lengthwise of the arm, a scale coöperating with the indicator, and means coöperating with the scale and adapted to be set with respect thereto so that the tip of one of the fingers 10 will contact therewith.
6. A device for indicating the length and hang of a coat sleeve embodying an indicator for designating a point to be indicated or marked upon the body of a coat, 15 means for releasably attaching the indicator to the arm of a person whereby the indicator may be adjusted in a direction lengthwise of the arm, a scale coöperating with the indicator, and an element adjustably connected with the scale and adapted to be 20 positioned to be engaged by the tip of one of the fingers, said scale being pivotally connected with the indicator to depend therebelow.
- 25 7. A device of the character described embodying an arm encircling portion, and an indicator connected thereto and disposed adjacent the hand for designating a point to be indicated or marked upon the body of 30 a coat, whereby the length and hang of a sleeve may be determined when the coat is not being worn.
8. A device of the character described embodying an arm encircling portion, an 35 indicator connected thereto and disposed adjacent the hand for designating a point to be indicated or marked upon the body of a coat, whereby the length and hang of a sleeve may be determined when the coat is 40 not being worn, and a measuring device connected with the indicator disposed adjacent to the hand and adapted to coöperate with the tip of one of the fingers.
9. A device of the character described 45 embodying an arm encircling portion, an indicator connected thereto and disposed adjacent the hand for designating a point to be indicated or marked upon the body of a coat, whereby the length and hang of a 50 sleeve may be determined when the coat is not being worn, a freely swinging scale depending below the indicator and extending beyond the fingers, and an element adjustable with respect to the scale and into engagement with one of the finger tips.
- 55 10. The combination of a sleeve section, means at one end thereof for adjustably securing the same upon the arm, and an indicator connected to the lower end of the 60 sleeve for designating upon the body of the coat the exact position the corner formed by the front and lower edges of the sleeve should assume with respect to the body of the coat when the coat is not being worn 65 and when the coat sleeve is being inserted.
11. The combination of a sleeve section, means at one end thereof for adjustably securing the same upon the arm, an indicator connected to the lower end of the 70 sleeve for designating upon the body of the coat the exact position the corner formed by the front and lower edges of the sleeve should assume with respect to the body of the coat when the coat is not being worn and when the coat sleeve is being inserted, 75 and means connected with said indicator and coöperating with the tip of one of the fingers for determining the length of the other coat sleeve.
12. The combination of a fabric sleeve 80 section, means at the upper end thereof for causing the same to be drawn about the arm and being yieldable to permit the sleeve section to be adjusted upon the arm, and an indicator secured to the lower end of the 85 said sleeve section for designating upon the body of the coat at the bottom of the sleeve, the correct hang of the coat sleeve.
13. The combination of a fabric sleeve 90 section, means at the upper end thereof for causing the same to be drawn about the arm and being yieldable to permit the sleeve section to be adjusted upon the arm, and an indicator secured to the lower end of the 95 said sleeve section for designating upon the body of the coat at the bottom of the sleeve, the correct length of the coat sleeve.
14. The combination of a fabric sleeve 100 section, means at the upper end thereof for causing the same to be drawn about the arm and being yieldable to permit the sleeve section to be adjusted upon the arm, and an indicator secured to the lower end of the 105 said sleeve section for designating upon the body of the coat at the bottom of the sleeve, the correct hang and length of the coat sleeve.
15. The combination of a fabric sleeve 110 section, means at the upper end thereof for causing the same to be drawn about the arm and being yieldable to permit the sleeve section to be adjusted upon the arm, an indicator secured to the lower end of the sleeve section for designating the location 115 of an indication to be made upon the body of the coat at the bottom of the sleeve section to designate the correct hang and length of the coat sleeve, and a measuring device connected with the said indicator for measuring the distance therefrom to the tip 120 of the thumb.
16. The combination of a fabric sleeve 125 section, means at the upper end thereof for causing the same to be drawn about the arm and being yieldable to permit the sleeve section to be adjusted upon the arm, an indicator secured to the lower end of the sleeve section for designating the location 130 of an indication to be made upon the body of the coat at the bottom of the sleeve sec-

tion to designate the correct hang and length of the coat sleeve, and a measuring device connected with the said indicator for measuring the distance therefrom to the tip 5 of the thumb, the said measuring device embodying a depending scale pivotally connected with the indicator, a gage adjustable

upon the scale and means for securing the gage in its adjusted position.

In testimony whereof I have signed my 10 name to this specification, on this 14th day of September, A. D. 1920.

JOHN C. CARLSON.
